Andrew D. Bochner

CLAIM

The ornamental design for a game board, as shown and described.

DESCRIPTION

FIG. 1 is a top, front left-side perspective view of the game board;

FIG. 2 is a top plan view thereof;

FIG. 3A is a top plan view of the left side of FIG. 2, at an enlarged scale;

FIG. 3B is a top plan view of the right side of FIG. 2, at an enlarged scale;

FIG. 4 is a front elevation view thereof, the rear, left side and

right side elevation views being identical; and,

FIG. 5 is a bottom plan view thereof.

In the drawings, the broken lines are for the purpose of illustrating environment only, and form no part of the claimed design.

1 Claim, 5 Drawing Sheets
